CLAIM

The ornamental design for a carrying container, as shown and described.

DESCRIPTION

FIG. 1 is a top perspective view of a carrying container of my new design, shown in a closed position;
FIG. 2 is a bottom perspective view thereof;
FIG. 3 is a left side view of the carrying container, the right side being a mirror image thereof;
FIG. 4 is a front side view of the carrying container, the rear side being a mirror image thereof;
FIG. 5 is an exploded top perspective view, showing details inside the lower portion not visible when in a closed position;
FIG. 6 is an exploded bottom perspective view thereof, showing details inside the upper portion not visible when in a closed position;
FIG. 7 is a bottom perspective view of the lower portion of a carrying container;
FIG. 8 is a top, front perspective view thereof;
FIG. 9 is a top, rear perspective view thereof;
FIG. 10 is a top view of the lower portion of the carrying container;
FIG. 11 is a bottom view of the lower portion of the carrying container;
FIG. 12 is a left side view of the lower portion of the carrying container, the right side being a mirror image thereof;
FIG. 13 is a front side view of the lower portion of the carrying container, the rear side being a mirror image thereof;
FIG. 14 is a top perspective view of the upper portion of a carrying container;
FIG. 15 is a bottom perspective view thereof, showing details inside the upper portion not seen when in a closed position;
FIG. 16 is a bottom view of the upper portion of the carrying container;
FIG. 17 is a top view of the upper portion of the carrying container;
FIG. 18 is a left side view of the upper portion of the carrying container, the right side being a mirror image thereof; and,

(Continued)

FIG. 19 is a front side view of the upper portion of the carrying container, the rear side being a mirror image thereof.
